UNITED STATES PATENT OFFICE.

GEORGE W. HIMLER, OF LATROBE, PENNSYLVANIA, ASSIGNOR OF ONE-HALF TO
GEORGE B. MEYERS, OF DERRY, PENNSYLVANIA.

LOCK.

1,117,846.

Specification of Letters Patent.

Patented Nov. 17, 1914.

Application filed May 9, 1914. Serial No. 837,577.

To all whom it may concern:

Be it known that I, GEORGE W. HIMLER, a citizen of the United States, residing at Latrobe, in the county of Westmoreland and State of Pennsylvania, have invented 5 certain new and useful Improvements in Locks, of which the following is a specification.

This invention relates to locks.

10 The object of this invention is the provision of a lock which eliminates the necessity of the use of springs or other like resilient actuating mechanism.

15 A further object of this invention is the provision of a lock in which the locking bolt thereof is operated by a sliding weight disposed within the lock casing.

20 A further object of this invention is the provision of latch mechanism which is adapted to prevent the retraction of the locking bolt without the use of a key.

25 A further object of this invention is to improve and simplify devices of this character rendering them comparatively simple and inexpensive to manufacture, reliable and efficient in use, and readily operated.

30 With the above and other objects in view this invention resides in the novel features of construction, formations, combinations and arrangements of parts to be hereinafter 35 more fully described, claimed and illustrated in the accompanying drawings, in which:

Figure 1 is a face view of my improved lock with the closing plate removed, showing 40 the locking bolt retracted. Fig. 2 is a similar view showing the locking bolt extended. Fig. 3 is a longitudinal sectional view of 45 my improved lock showing the opposite side of the mechanism to that shown in Figs. 1 and 2. Fig. 4 is a transverse sectional view taken on the line $x-x$ of Fig. 1. Fig. 5 is a similar view taken on the line 6—6 of Fig. 1.

45 Referring to the accompanying drawings by similar characters of reference throughout the several views, the numeral 6 designates in general my improved lock, which consists of a lock casing 7 of substantially 50 rectangular formation, having a removable plate or closure 8 by means of which access can be had to the casing and the lock mechanism contained therein. An operating weight 9 of substantially rectangular formation having a forked extension 10 is slidable 55 within said casing. This operating weight

9 is provided with a vertically extending central slot 11 for engagement with a boss 12 formed upon the casing and providing a means for the attachment of the closure plate 8. An additional slot 13 is formed in said 60 sliding weight 9 adjacent the slot 11 for the reception of the bearing 14 of a double knob lever 15, which permits the vertical movement of said weight 9 without interfering therewith. This knob lever 15 is provided 65 with oppositely extending arms 16, which engage a shoulder 17 provided upon said weight 9 and upon the rotation of the knob (not shown in the drawing) in either direction. These arms 16 by their contact with 70 the said shoulder raise said weight 9 for a purpose to be later explained. A locking bolt 18 is slidable within the casing, through a slot 19 formed therein, and is designed to be limited in its inward movement by contact with the shoulder 20 provided on the 75 forked extension 10.

The weight 9 is provided with a Z-shaped recess 21 in which is disposed the depending arm 22 of a bell crank lever 23, the latter being journaled at 24 in the upper end of said casing 7 adjacent one of the side walls thereof. The horizontal arm 25 of the bell crank lever 23 fits within an extension 26 of the groove 21, and is adapted to engage 80 the shoulders 27 thereof, so that upon the vertical movement of the weight 9, the said arm 22 of the bell crank lever will be swung laterally with respect to said casing 7. The lower end of the arm 22 is disposed within 85 either of the grooves 28 of the locking bolt 18, in order that, when the arm 22 moves laterally of the casing 7, the locking bolt 18 will consequently be moved laterally and extended through the slot 19, or retracted 90 within the casing. The shoulder 20 is extended as at 29 to contact with the arm 22 of the bell crank lever instantaneously upon the engagement of the bolt 18 with the shoulder 20, in order to relieve the latter 100 of the concussion of the said bolt 18 therewith, upon operation of the lock under undue pressure.

An inclined boss 30 is formed in the groove 21 adjacent one side of the weight 9 and is 105 designed to engage the slot 31 formed in a sliding latch 32. The inner end of the latch 32 is curved to conform to the curvature of the arm 22 of the bell crank lever, while the opposite end of said latch is formed an- 110

gularly, as at 33, to contact with the forward end of the boss 30 so that when the opposite end thereof is in engagement with the bell crank lever, the inward movement 5 of the locking bolt 18 is prevented. This latch 32 is formed with a depending extension 34 provided with a key notch 35 for the reception of a key (not shown) to be used in operating the latch 32 to assume the positions shown in Figs. 1 and 2. In Fig. 1 the latch is in an inoperative position which permits the movement of the locking bolt 18 in either direction upon operation of the door knob while, as shown in Fig. 2, the 10 latch is in contact with the boss 30 and arm 22 of the bell crank lever which prevents the retraction of the locking bolt 18 without use of a key corresponding to the notch 35. When in the position shown in Fig. 2 the 15 latch 32 is limited in its downward movement by the offset portion 36 of the before described shoulder 20.

It should be noted that the grooves 28 are so arranged that it is possible to reverse the position of the locking bolt, within the casing 7, without necessitating any changes in the lock mechanism.

The operation of the device is as follows: The locking bolt 18 is normally extended 30 to engage the keeper, and when it is desired to lock the same against movement the key is operated to force the latch 32 against the rear side of the arm 22 of the bell crank lever 23 as shown in Fig. 2. When in this 35 position the rear end of said latch contacts with the stop 30 which obviously holds the bolt 18 in its extended position and prevents the opening of the door except by means of the key. When it is desired to 40 unlock the door the key is inserted through the key hole into engagement with the extension 36 of the latch and is rotated in a reverse direction which obviously raises the shoulder 33 of the latch 32 above the boss 45 30 until the slot 31 engages said boss 30 which obviously holds the latch 32 in inoperative position. The door knob (not shown in the drawing) is then rotated causing the arms to raise the weight thereby operating 50 the bell crank lever 23 to retract the bolt 18 and to permit the opening of the door. It will be noted that it is impossible to open the door without first rotating the door knob to retract the bolt 18 and that it is also 55 necessary to operate the door knob to operate the bolt 18 when the door is being closed.

It is understood that various minor changes in the specific details of construction can be resorted to within the scope of

the appended claims without departing from or sacrificing any of the advantages of the invention.

From the foregoing disclosures it will be manifest that a lock of the nature described 65 is provided which will fulfil all of the necessary requirements of such a device.

What is claimed is:—

1. In a lock such as described, a sliding weight, a sliding locking bolt, a bell crank 70 lever connecting said sliding weight and locking bolt, means for raising and lowering said sliding weight, and a slidable latch adapted to engage the sliding weight and bell crank lever. 75

2. In a lock such as described, a casing, a weight slidable therein, a locking bolt slideable within said casing at right angles to the path of movement of said sliding weight, means for raising or lowering said sliding 80 weight, a bell crank lever engaging said sliding weight and locking bolt, a boss formed upon said sliding weight, a latch designed to engage said boss and contact with the bell crank lever, and means for operating said latch. 85

3. In a lock such as described, a casing, a weight slidable therein, said weight having a groove therein, a latch slideable in said groove, a bell crank lever movable in said groove, a locking bolt engaging said bell crank lever, a boss formed upon the weight and adapted to engage the notch in said sliding latch, and means for operating the sliding latch to engage the boss and bell 95 crank lever.

4. In a lock such as described, a casing, a weight slidable in said casing, a reversible locking bolt slidable in said casing and connected with the sliding weight, a bell crank 100 lever pivoted within the casing and engaging grooves in the sliding weight and reversible locking bolt, a shoulder provided upon said sliding weight for limiting the movement of the bell crank lever, a boss 105 formed upon the sliding weight, a latch having a slot therein slideable upon said boss, means for operating the latch to contact with the end of the boss and one arm of the bell crank lever, for holding the locking bolt 110 at one limit of its movement, and a shoulder provided upon said sliding weight for limiting the movement of said latch.

In testimony whereof I affix my signature in presence of two witnesses:

GEORGE W. HIMLER.
